US0D1047162S

(12) **United States Design Patent** (10) **Patent No.:** **US D1,047,162 S**
(45) **Date of Patent:** **** Oct. 15, 2024**

(54) **PHOTOBIMODULATION THERAPY DEVICE**

- (71) Applicant: **Joovv, Inc.**, San Clemente, CA (US)
(72) Inventor: **Greg Pfiffner**, San Clemente, CA (US)
(73) Assignee: **Joovv, Inc.**, San Clemente, CA (US)
(***) Term: **15 Years**
(21) Appl. No.: **29/808,872**
(22) Filed: **Sep. 23, 2021**

Related U.S. Application Data

- (63) Continuation-in-part of application No. 17/027,472, filed on Sep. 21, 2020, now abandoned.

(57) **CLAIM**

The ornamental design for a photobiomodulation therapy device as shown and described.

DESCRIPTION

FIG. 1 is a front, first side, and top perspective view of a photobiomodulation therapy device embodying the new design;

FIG. 2 is a back, second side, and top perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The uniform repeating broken lines depict portions of a photobiomodulation therapy device in which the claimed design is embodied and form no part of the claimed design.

1 Claim, 8 Drawing Sheets
